UNITED STATES PATENT OFFICE

147,297

DESIGN FOR AN EARRING

Alfred Philippe, Scarsdale, N. Y., assignor to Tri-fari, Krussman & Fishel, Inc., New York, N. Y.

Application July 26, 1946, Serial No. 131,993

Term of patent 7 years

(Cl. D45—9)

To all whom it may concern:

Be it known that I, Alfred Philippe, a citizen of the United States of America, residing in Scarsdale, county of Westchester, and State of New York, have invented a new, original, and ornamental Design for an Earring, of which the following is a specification, reference being had to the accompanying drawing, forming part thereof.

Fig. 1 is a plan view of an earring, showing my new design.

Fig. 2 is an edge view thereof.

I claim:

The ornamental design for an earring substantially as shown.

ALFRED PHILIPPE.
